SWITCH MECHANISM

Hans Sengebusch, Villa Park, Ill., assignor to
 Associated Electric Laboratories, Inc., Chicago,
 Ill., a corporation of Delaware

Application July 29, 1935, Serial No. 33,705

11 Claims. (Cl. 179—27.52)

The present invention relates in general to automatic switching apparatus, but is particularly concerned with the production of a switch in the nature of an improvement upon that type 5 having a horizontal motion and then a rotary motion in a vertical plane at right angles to the horizontal motion.

The main object of the present invention is to provide an automatic switch of simple structure, 10 which is both rapid and accurate in its operations.

Another object of the invention is to provide improved mounting arrangements for mounting the various switches with respect to their associated switch banks.

In the specific embodiment of the invention, the 15 operating motor comprises a spring which is wound up during the restoring movement of the switch to replace the energy expended by a previous operation. This spring motor actuates the 20 wipershaft first in a step-by-step horizontal movement and then in a downward step-by-step rotary movement under the control of an escapement mechanism and a single operating magnet. A 25 changeover magnet controls a locking arrangement by means of which the wiper shaft is normally locked against rotary motion, normally permitting, however, horizontal movement of the 30 wiper shaft. When the changeover magnet operates the locking arrangement, the wiper shaft is then locked against further horizontal motion and is permitted to rotate.

Another object is to provide a switch of the foregoing type which may be readily modified to operate spring combinations at any desired level 35 or combination of levels of the wipers.

One of the features of the invention relates to an improved escapement mechanism wherein a holding pawl in addition to holding the shaft in its operated positions also acts as a part of the 40 escapement mechanism in cooperation with the armature of the operating magnet.

The invention is disclosed in four sheets of drawings which show various views of the switch mechanism and mounting arrangement.

Fig. 1 shows a front view of one of the switches mounted in place on an upright carrying the switchbanks and female jacks for such switches.

Fig. 2 is a bottom view of the switch mechanism.

Fig. 3 is an end view of the switch mechanism looking from right to left of Fig. 1.

Fig. 4 is a top view of the switch mechanism and upright with the switch mechanism a little to the left of its normal mounting position on the 55 upright.

Fig. 5 is a sectional view as seen from line 5—5 of Fig. 4.

Fig. 6 is a sectional view as seen from line 6—6 of Fig. 4.

Fig. 7 is a sectional view of a portion of the 5 switch frame in its mounting position on the upright on the line A—A of Fig. 8.

Fig. 8 shows a side view of the upright with a 10 switch mechanism placed in its initial position preparatory to mounting the switch on the upright in its mounting position.

Fig. 9 shows a sectional view of the wiper shaft assembly.

Figure 9A is a detailed view of the cap 42.

Figure 9B is a separate view of the sleeve 21. 15

The switch frame for mounting the operating magnets and mechanisms is preferably cast in a form somewhat resembling a ladder with two side portions 1 and 2 and two center portions 1'.

The base side portion 2 is shown partly in full 20 and dotted lines in Fig. 8, while the top side portion 1 is shown more clearly in Fig. 3. The two center portions 1' and 1' are shown more clearly in Fig. 2, while only the front portion 1' is shown in Fig. 1. The changeover magnet 47 and the 25 operating magnet 48 are mounted on the rear center portion 1' while the changeover armature 65, the eleventh position operating lever 55, and the level operating levers 59 and 60 are rotatably mounted on the front center portion 1'. A plate 30

3 fastened to the side portions 1 and 2 is provided 35 for mounting the off normal spring assembly 53, the changeover spring assembly 71, and the eleventh position spring assembly 57. An L-shaped plate 3' directly below plate 3 (see Fig. 3) 35

secured to the side portions 1 and 2 is provided for mounting the restoring magnets 50 and retaining spring 74 for armature 73 of the operating 40 magnet 48. A plate 4, as seen in Fig. 2, secured to the side portions 1 and 2 is provided for mounting the spring assemblies 63 and 64 operated by

rubber bushings 61 and 62 on the level operating levers 59 and 60. The base side portions 2 of the cast frame is provided with a key hole locking 45 lug 46 to properly position and lock the frame to the upright 8. The vertical plate 7 and guide plate 7' are fastened to frame 2 by screws 2'. The changeover armature 65 is pivoted in a hole drilled in frame 2 and in a lug on the front portion 1'. The off normal armature 51 is pivoted 50 on a pin extending through frame 2 as shown in Fig. 5. The restoring armature 80 is pivoted on a pin extending from frame 2 to frame 1. The operating armature 73 is pivoted on a pin extending from frame 1 to a lug on the rear section 1'. 55

The stationary changeover guide 69 is fastened to a lug on the front center section 1' and to the frame 1 by means of screws. An adjustable back stop 58 is secured to front center section 1' to limit the front stroke of the eleventh position armature 55 while a lug on this section limits the back stroke. The male jack assembly 90 is mounted on the rear of frame 1, while near the center of frame 1 the operating interrupter springs 77 and restoring interrupter springs 84 are mounted. The frame 1 has a recess in which the slotted spring adjusting plate 81' is fastened to enable varying tension to be applied to spring 81 which restores the restoring armature 80. The restoring armature back stop 82 and the operating armature back stop 75 are similarly and adjustably fastened to frame 1. Screw 92 extending through frame 1 is provided for holding a lug 93 which limits the stroke of the pawl 41 pivoted on armature 80. Pawl 41 is pivoted on armature 80 and is provided with a tail 85 which strikes the adjustable stop 87 on frame 1 when armature 80 is restored by spring 81 in order to remove pawl 51 from the teeth 36 of the barrel 27. The front center part of frame 1 has a cone shaped portion in which the sleeve 37 of barrel 27 freely rotates and around which the operating spring 43 is wound. Holding pawl 40, normally in engagement with teeth 36, is pivotally mounted in frame 1 and has an arm 79 which engages the lug 79' on armature 73 so that when armature 73 is operated to engage teeth 36 on barrel 27 the pawl 40 is disengaged from the teeth to permit rotation of barrel 27. Armature 80 has a rubber bushing 83 for operating interrupter springs 84 and armature 73 has a rubber bushing 76 for operating interrupter springs 77. Changeover armature 65 has a flat restoring spring 68 which rests against the heel piece of the changeover magnet 47 to restore the armature.

The wiper shaft assembly shown in Fig. 9 comprises a shaft 16 upon which the elongated cam 20 is rigidly secured by means of a pin passing through the cam and shaft. The cam 20 has a cut-out portion, shown more clearly in the cross section of Fig. 5, in which the changeover dog 29 of armature 65 normally rests below the notches of the sleeve 21. This straight edge formed by the cut-out portion of cam 20 causes the operation of the eleventh position cam lever 30 in case the shaft 16 is rotated in its eleventh step. Metal washers 20' are placed over the shaft 16 on either end of elongated cam 20. Sleeve 21 has ten notches cut in the edge of its cut-out portion, as shown, and the changeover dog 29 is raised into one of these notches when the changeover magnet 47 is operated. A portion of the sleeve 21 is bent into a straight edge 21' which normally slides in the slot of guide 32 fastened to plate 7. By means of edge 21' and the slot in guide 32 the sleeve 21 is permitted to move horizontally but is prevented from rotating with the shaft 16. A metal collar 33 rigidly secured to sleeve 21 acts as a bearing in which the shaft 16 rotates. A similar flanged collar 34 fits into the right-hand end of sleeve 21 and is secured to sleeve 21 by means of screws. The flanged collar 34 also acts as a bearing for shaft 16 and is provided with an oil retaining assembly 34' comprising a felt and a metal washer. In a like manner the spacing collar 35 is provided with an oil retaining assembly 35'. A metal block 22 secured to shaft 16 by screw 23 is provided with a pin 26 upon which the swivels 25 are rotatably positioned; the pin 26 being held in block 22 by means of screw 24 (see Fig. 6) in such

a manner as to allow the swivels 25 to rotate freely on the pin. A slotted barrel 27 open at one end and having a sleeve 37 (Fig. 9) at the other end permits the shaft assembly to slide horizontally and rotate freely therein. The teeth 36 cut in the periphery of the flange of sleeve 37 and pawls 40 and 41 (Fig. 6) are the medium by means of which the barrel 27 is rotated. Barrel 27 has two spiral slots 38 and 39 cut therein. Slot 38 acts as a guide for the innermost swivel 25 to provide horizontal movement to the shaft assembly when the barrel 27 is rotated at a time when the wiper assembly is locked against rotary movement. Slot 39 is provided in order to have access to set screw 23 so that the block 22 may be properly adjusted on shaft 16. A cap 42 screws on the end of sleeve 37 and is held in place by a pin passing through cap 42 and sleeve 37. Cap 42 is provided with curved slots on its outer edge for holding the tensioned actuating escapement spring 43 at one end while the spring is held at its other end by a lug on frame 1. The outermost swivel 26 rotates and slides between the edges of armature 65 and guide 69 to produce horizontal movement of shaft 16 when armature 65 is in its restored position. When armature 65 is operated dog 29 of armature 65 enters one of the notches of sleeve 21 to prevent further horizontal movement of shaft 16 and the armature 65 is raised to permit the outermost swivel to pass under armature 65 when the operating magnet is operated to rotate the barrel 27. Since the swivels 25 are first moved horizontally and then rotated and since these swivels are secured to shaft 16 the corresponding movements are imparted to shaft 16.

Fixed to sleeve 21 is a flat plate 95 drilled with holes 97 which correspond to each horizontal stepping position of shaft 16. Studs 96 are secured in predetermined ones of the holes 97 and such such studs by engaging the rollers in levers 59 and 60 during horizontal movement of the shaft 16 rotate such levers to operate spring assemblies 63 and 64. By studs 96 in any predetermined hole 97 the level operating springs 63 or 64 may be operated at any predetermined level or horizontal stepping position of the shaft. The switch mechanisms are mounted on vertical L-shaped uprights 8-9 in a horizontal position one above the other. The side 8 of the upright 8-9 is bent at right-angles to the side 9 and the latter side is bent at 9' to provide a mounting space for the female-jack assemblies 44. A key-hole slot 45 is cut in side 8 for each switch mounting space and cooperates with the key locking lug 46 fastened to the switch frame to assist in positioning and locking a switch mechanism in its proper position on the upright. In addition each switch mounting space in side 8 has a rectangular cut out portion (see Fig. 8) in which the rectangular portion of plate 7 of the switches fit to form a tongue and groove locating means. Semi-circular openings on the edge of side 8 are provided for the switch frame rods 5 and 6 to assist in properly locating the switch mechanism. Strowger bank assemblies comprising sets of bank contacts 13 are secured to side 8 of the upright by means of bank rods 10 and 11 and nuts 10' and 11'. A locking lever 17 is mounted on bank rod 10 so as to lock the bank assembly to the switch mechanism when the lever 17 is rotated as shown in the dotted lines of Fig. 8. The outer metal plates on the bank sets have U-shaped extensions which also act as guides for the switch frame rods 5 and 6 so that the wipers of the switch mechanism are properly positioned with respect to the

bank contacts when locking lever 17 is in locking position. As seen in Fig. 1, a support 14 secured to switch frame rods 5 and 6 by means of screws 14' has a bronze bearing 15 to support the shaft 16. The switch frame rods 5 and 6 extend through holes in the left side of the cast switch frame to the right side of the cast switch frame where such rods are held in place by screws 5' and 6'. This mounting arrangement was designed primarily to provide an easy means of quickly removing and replacing the switch mechanisms on the switch frame uprights to which the banks 13 are permanently mounted. In addition this mounting arrangement insures the correct positioning of the wipers with regard to the banks. In order to mount a switch mechanism in one of the mounting spaces on an upright the shaft is held in a horizontal position and the locking lug 46 is inserted in the circular portion of the key-hole slot 45 and then pushed so that the upper edge of lug 46 (as seen in Figs. 7 and 8) engages the narrow edges of slot 45 in upright 8. As the switch mechanism is pushed to the left (Fig. 8), the rectangular portion of the plate 7 enters the rectangular cut out portion of upright 8 and the rods 5 and 6 enter into the semi-circular recesses in upright 8. The lever 17 is then rotated to lock the switch to the banks 13. The switch is now securely held in place by lug 46, guide plate 7' and lever 17. To remove a switch the lever 17 is rotated and the switch mechanism is moved to the right until the lug 46 is opposite the circular portion of key-hole slot 45 from which point the switch may be removed.

The circuits to the magnets, wipers, and springs of the switch mechanism are taken through jack assemblies 90 and 44 to a relay group which controls the operation of the switch. Any relay group is capable of controlling any switch mechanism when connected together through the jack assemblies.

Having described the detail construction and assembly of the switch mechanism an explanation will now be given of its operation. In normal position, the shaft 16 is in such position that wipers 19 are to the right of the right-hand row, or first level, of bank contacts 13. Fig. 1 shows the shaft 16 and wipers 19 in their tenth level or the tenth horizontal stepping position. In normal position of shaft 16 the flange 34 operates arm 31 and armature 51 to close and open certain of the spring contacts in off normal spring assembly 53. In order to operate the mechanism in its first or horizontal movement the circuit to operating magnet 48 is completed from the associated relay group (not shown). In response to each impulse magnet 48 operates its armature 73 and positions its end in the rotating path of teeth 36. The lug 79 of armature 73 engages arm 79 of the holding pawl 40 to cause the latter to rotate and disengage from teeth 36 on barrel 27 thereby causing the barrel 27 to rotate, due to tension on spring 43, one-half step to engage the end of armature 73. When operating magnet 48 deenergizes the end of armature 73 is withdrawn from the path of teeth 36 but the holding pawl by this time is in a position to engage the next tooth with the result that another half step is taken on deenergization of magnet 48. Therefore, for each operation of magnet 48, that is, one energization and one deenergization, barrel 27 is rotated one step. Each rotary step of barrel 27 at this time causes shaft 16 to move one step in a horizontal direction due to the outermost swivel 25 being held against rotary movement by

armature 65 and guide 69 while the innermost swivel 25 slides in the spiral groove 38 of barrel 27 when the latter rotates one step. In this manner the shaft and wipers are stepped in a horizontal direction in a number of steps corresponding to the number of operations of magnet 48. On the first horizontal movement of the shaft, flange 34 is moved away from arm 31 to cause the off-normal armature 51 and off normal springs 53 to operate. In case one of the level marking studs 96 is in position corresponding to the position the shaft has stopped in then the corresponding level springs 63 or 64 are operated.

After the horizontal movement, changeover magnet 47 operates armature 65 above the outermost swivel 25, projects dog 29 in one of the notches of sleeve 21 and operates arm 66 and spring assembly 11. Due to the projection of dog 29 in one of the notches of sleeve 21 the shaft and wipers are held against further horizontal movement. Now, when operating magnet 48 is again operated to rotate barrel 27, the shaft 16 and wipers rotate therewith since the shaft is locked against horizontal movement and the swivel is permitted to pass under armature 65 due to the energized condition of changeover magnet 47. Each operation of magnet 48, therefore, allows the escapement spring 43 to rotate the barrel 27 and shaft 16 one step, the wipers 19 being stepped in engagement with successive bank contacts 13 in the selected level, or row, by successive operations of operating magnet 48. After the first rotary step of shaft 16 the dog 29 rides on cam 20 to maintain the changeover armature in operated position.

The switch shaft 16 and wipers are restored by operations of the restoring magnet 50 which intermittently operates its armature 80 and pawl 41 to step the barrel 27 and retention spring 43. Each time armature 80 is operated pawl 41 engages one of the teeth 36 to rotate barrel 27 clockwise as seen in Fig. 6, the locking pawl being spring actuated rides over the teeth 36 to prevent any anti-clockwise movement of the barrel 27. The shaft 16 and barrel 27 are first rotated together until the outermost swivel 25 engages the guide plate 69 at which time the dog 29 is permitted to drop off of cam 20 and disengage from the notch of sleeve 21. Further rotation of barrel 27 now causes the shaft 16 to be restored horizontally step by step until the off normal armature 51 operates the off normal springs to open the circuit to restoring magnet 50. Each operation of armature 80 also causes the rubber bushing 83 to operate interrupter springs 84 to open the circuit restoring magnet 50 and cause its intermittent operations. Similar interrupter springs 77 are controlled by bushing 76 on armature 73 of the operating magnet 48 so that this magnet may be intermittently operated if desired.

As will be seen in the foregoing the switch shaft is stepped first in a horizontal direction and then in a rotary direction to select a certain set of bank contacts and that a single operating magnet controls the escapement which produces both movements, while a changeover magnet determines when the horizontal movement is to end and the rotary movement is to begin. A single restoring magnet also restores the shaft both rotary and horizontally to normal position and retensions the escapement operating spring. The switch as shown is designed so as to be capable of directive control in both its movements, to be capable of directive control in its horizontal movement and automatic in its rotary movement, or automatic

in both movements dependent upon slight circuit changes in the associated relay group. Such switch structure may therefore be used as a connector, a selector, or as a finder.

5. What is claimed is:

1. In a switch mechanism, a sleeve having notches, a wiper shaft rotatably mounted in said sleeve, a barrel rotatably mounted on said shaft, a spiral slot in said barrel, a swivel fixed to said shaft and slidably positioned in the slot of said barrel, a changeover armature having a straight horizontal edge and a locking arm, a second swivel fixed on said shaft and slidably positioned along the edge of the changeover armature to prevent rotary movement of the shaft, means for rotating said barrel to cause the first swivel to follow the spiral slot in the barrel and the second swivel to follow the straight edge of the changeover armature to impart horizontal movement to said shaft, and means for operating the changeover armature to position the locking arm in one of the notches of said sleeve to prevent further horizontal movement of said shaft and to raise the straight edge of the changeover armature to permit rotary movement of said swivels and shaft in response to further rotation of said barrel.

2. In a switch mechanism, a sleeve having notches, a wiper shaft rotatably mounted in said sleeve, a barrel rotatably mounted on said shaft, a spiral slot in said barrel, a swivel fixed to said shaft and slidably positioned in the slot of said barrel, a changeover armature having a straight horizontal edge and a locking arm, a second swivel fixed on said shaft and slidably positioned along the edge of the changeover armature to prevent rotary movement of the shaft, means for rotating said barrel to cause the first swivel to follow the spiral slot in the barrel and the second swivel to follow the straight edge of the changeover armature to impart horizontal movement to said shaft, means for operating the changeover armature to position the locking arm in one of the notches of said sleeve to prevent further horizontal movement of said shaft and to raise the straight edge of the changeover armature to permit rotary movement of said swivels and shaft in response to further rotation of said barrel, and a cam fixed to said shaft and rotated therewith to maintain the changeover armature in its operated position.

3. In a switch mechanism, a wiper shaft having movements in two planes, a sleeve rotatably mounted on said shaft, means for locking said shaft against movement in one plane, means for locking said shaft against movement in the other plane, and means for rotating said sleeve to move said shaft in one or the other plane dependent upon the condition of said locking means.

4. In a switch mechanism, a wiper shaft having movements in two planes, a sleeve rotatably mounted on said shaft, means for locking said shaft against movement in one plane, means for locking said shaft against movement in the other plane, and a single operating magnet for operating said sleeve to move said shaft in one or the other plane dependent upon the condition of said locking means.

5. In a switch mechanism, a wiper shaft having movements in two planes, a sleeve rotatably mounted on said shaft, means for locking said shaft against movement in one plane, means for locking said shaft against movement in the other plane, a normally tensioned spring and an escapement for rotating said sleeve, and a single operating magnet for operating said escapement

to rotate said sleeve to move said shaft in one or the other plane dependent upon the condition of said locking means.

6. In a switch mechanism, a wiper shaft having horizontal and rotary movements, a barrel rotatably mounted on said shaft, a spiral slot in said barrel, a swivel fixed to said shaft and slidably positioned in said slot, means for locking said shaft against rotary movement, means for locking said shaft against horizontal movement, and means for rotating said barrel to cause said swivel to follow said spiral slot and impart horizontal movement to said shaft when locked against rotation and to cause said shaft to rotate with said barrel when said shaft is locked against horizontal movement.

7. In a switch mechanism, a wiper shaft having horizontal and rotary movements, a barrel rotatably mounted on said shaft, a spiral slot in said barrel, a swivel fixed to said shaft and slidably positioned in said slot, means for locking said shaft against rotary movement, means for locking said shaft against horizontal movement, and means for rotating said barrel to cause said swivel to follow said spiral slot and impart horizontal movement to said shaft when locked against rotation and to cause said shaft to rotate with said barrel when said shaft is locked against horizontal movement, and a changeover magnet for controlling both said locking means.

8. In an automatic switch having a wiper shaft and means for moving said shaft into a plurality of positions, stationary contact spring assemblies, each including an operating member for operating the contact springs of its associated assembly, and means carried by said shaft for engaging said operating members to cause them to operate their respective contact springs as said shaft is moved, said last means comprising a plate having holds corresponding to the positions of said shaft and studs mountable in said holes as desired to engage desired ones of said operating members in desired positions of said shaft, whereby operation of the contact springs of any assembly may be secured in any position of said shaft.

9. In a switch mechanism, a spring actuated escapement wheel having teeth in its periphery, an operating armature having a bent portion for projection into the path of rotation of the teeth of said wheel when the armature is operated, a spring actuated holding pawl for said wheel controlled by said armature, means responsive to the operation and restoration of said armature for operating said bent portion and said pawl as an escapement mechanism in cooperation with said teeth to rotate said wheel step by step in one direction, a restoring pawl, means for operating said restoring pawl to engage said teeth and rotate said wheel step by step in another direction, said holding pawl holding said wheel after each step rotation in either direction.

10. In a switch mechanism, a switch shaft, an escapement mechanism for said shaft comprising a pawl and a separate armature each cooperating with the teeth on an escapement wheel, means for operating said escapement mechanism to rotate said wheel and move said shaft in two different directions, a restoring pawl, means for operating said restoring pawl to rotate said wheel step by step in the opposite direction to restore said shaft, said pawl in said escapement mechanism cooperating with said restoring pawl to hold said wheel at each restored step.

11. In a switch mechanism, an escapement wheel having teeth in its periphery, a spring

5 actuated holding pawl therefor, an operating armature having a bent portion, means responsive to the operation of said armature for operating said holding pawl out of engagement with said teeth and for projecting the bent portion of said armature into the path of rotation of said teeth, means responsive to the restoration of said armature for restoring said holding pawl into the path of rotation of said teeth and for removing

said bent portion out of engagement with said teeth, and a spring for rotating said wheel half a step until one of said teeth engages said bent portion each time the armature is operated and for rotating said wheel the remainder of the steps until one of said teeth engages said holding pawl each time said armature is restored. 5

HANS SENGBUSCH.
